UNITED STATES PATENT OFFICE

153,892

DESIGN FOR A HYDRAULIC PRESS

Howard V. Mills, Columbus, Ohio, assignor to The
Denison Engineering Company, Columbus,
Ohio, a corporation of Ohio

Application March 25, 1948, Serial No. 145,339

Term of patent 14 years

(Cl. D63—1)

To all whom it may concern:

Be it known that I, Howard V. Mills, a citizen of the United States, residing at 1489 Ashland Avenue, Columbus, in the county of Franklin and State of Ohio, have invented a new, original, and ornamental Design for Hydraulic Press, of which the following is a specification, reference being had to the accompanying drawings, forming a part thereof, in which

Figure 1 is a perspective view looking towards the front of a hydraulic press, showing my new design.

Figure 2 is a perspective view looking towards the rear of the hydraulic press, showing my new design.

I claim:
The ornamental design for a hydraulic press, substantially as shown.

HOWARD V. MILLS.
